United States Patent Office

Des. 211,532
Patented June 25, 1968

211,532

SERVING TRAY OR THE LIKE

Harold P. Ashton, Providence, R.I., assignor to Rexall Drug and Chemical Company, Los Angeles, Calif., a corporation of Delaware

Filed Nov. 1, 1967, Ser. No. 9,246

Term of patent 14 years

(Cl. D44—10)

FIG. 2

FIG. 1

FIG. 5

FIG. 6

FIG. 4

FIG. 3

I claim:

The ornamental design for a serving tray or the like, substantially as shown.
